(57) **CLAIM**

The ornamental design for a display for a medical device, as shown and described.

DESCRIPTION

FIG. 1 is a front view of a first image for a display for a medical device showing the new design.

FIG. 2 is a front view of a second image thereof.

FIG. 3 is a front view of a third image thereof.

FIG. 4 is a front view of a fourth image thereof; and,

FIG. 5 is a front view of a fifth image thereof.

The appearance of the transitional image sequentially transitions between the images shown in FIGS. 1-5. The process or period in which one image transitions to another image forms no part of the claimed design.
